[57] **CLAIM**

The ornamental design for a fluid meter electronic flow
corrector module cover, as shown and described.

DESCRIPTION

FIG. 1 is a front perspective view of a fluid meter electronic flow corrector module cover showing my new design;

FIG. 2 is a left side elevational view thereof, the right
side being a mirror image thereto;

FIG. 3 is a front elevational view thereof;

FIG. 4 is a top plan view thereof;

FIG. 5 is a bottom plan view thereof; and

FIG. 6 is a rear elevational view thereof.
